UNITED STATES PATENT OFFICE.

WILLIAM W. HAWKINS, OF BROOKLYN, NEW YORK, ASSIGNOR TO WEBSTER ELECTRIC COMPANY, OF RACINE, WISCONSIN, A CORPORATION OF WISCONSIN.

IGNITION MAGNETO.

Application filed March 25, 1922. Serial No. 546,678.

This invention relates to magnetos and particularly to magnetos of the type which are used as ignition devices in connection with internal explosion engines.

5 The object of the invention is the provision of a magneto which will consist of relatively few parts of simple design and which will provide a spark of great intensity.

One of the features of the invention is the 10 provision of an inductor element on the rotor which will operate to alternately complete paths from the opposite magnet pole pieces to the extensions for the core of the transformer. Another feature of the invention 15 is the provision of a stationary coil mounted about the center of the transformer and through which the flux in the inductor extends. Another feature resides in the circuit arrangement provided in connection 20 with the primary coil of the transformer and the generator coil by means of which the advantages of the mechanical construction are utilized.

Further features and advantages will appear from time to time as the description of the invention progresses.

In the drawings:

Figure 1 shows a vertical longitudinal section through the device;

30 Figure 2 is a section on the line 2—2 of Fig. 1;

Figure 3 is a section on the line 3—3 of Fig. 1;

35 Figure 4 is a section substantially on the line 4—4 of Fig. 1, looking in the direction of the arrows and showing the interrupter connections for the magneto.

Figure 5 is a perspective view showing one 40 of the end plates, a portion of one of the extensions for the transformer core piece and the magnet pole pieces at one end of the magneto; and

Figure 6 is a circuit diagram showing the 45 relation of the coils and the interrupter.

46 Referring now to the drawings in which like reference characters indicate similar parts in the several views, 10, 11, 12, 13 and 14 represent permanent magnets of U shape. Magnets 10 and 13 are mounted outside of 50 and in engagement with magnets 11 and 14, respectively, while magnet 12 is mounted between and in engagement with magnets 10 and 13. The magnets 13 and 14 are provided with a pair of pole pieces 15 and 16 at the 55 opposite ends thereof, as indicated in Fig. 3.

These pole pieces 15 and 16 are formed of laminations of magnetic material in the usual manner, and are of substantially the same width as are the magnets 13 and 14. The opposite ends of the magnets 10 and 11 are 60 provided with similar pole pieces 17 and 18, shown only in dotted lines in Fig. 2. It is to be understood, however, that the magnets, pole pieces, inductor element and the coils of the magneto are symmetrically 65 arranged at opposite ends of the magneto.

Secured to the magnets 10 and 13, respectively, are the end plates 19 and 20. End plate 19 is provided with a boss 21 having an annular recess 22 within which is positioned the ball bearing 23 for the supporting pindle 24 at one end of the rotor. The boss 21 is also provided with an opening 25 through which the pindle 24 projects. The end plate 20 is provided with a boss 26, 70 similar to the boss 21, within which is the ball bearing 27 for the pindle 28 at the opposite end of the rotor. The boss 26 is also provided with an opening 29 through which projects a collar 30 mounted about the 75 pindle 28.

The rotor comprises the inductor element 31 made up of strips or laminations of magnetic material. Each of the plates forming the inductor element 31 has its opposite corners cut away so that the inductor 31 is substantially Z shape in form. Within the cut-away portions of the inductor and on the opposite sides of the central portion thereof is provided a mounting of non-magnetic material so that the entire rotor is substantially 80 cylindrical in form. The pintles 24 and 28 are secured to the rotor by having screw-threaded extensions 33 and 34, respectively, received by openings in the opposite ends of 85 the non-magnetic material 32.

Mounted in the space within the upper portion of the magnets 10 to 14, is a transformer comprising the core 35, primary coil 36 and secondary coil 37. The core 35 is 90 provided at the opposite ends thereof with the extensions 38 and 39, which terminate at the lower ends thereof in annular portions 40 and 41, respectively, which encircle the rotor. The extensions 38 and 39 and the 95 annular portions 40 and 41 are formed of laminations of magnetic material.

Mounted about the central portion of the inductor 31 is a generator coil 42. Coil 42 is arranged within a housing 43 of non- 100

magnetic material. The magnets, magnet pole pieces, rotor and the housing 43 are surrounded by the usual base 44 of non-magnetic material.

5 Within the base 44 at one end thereof is provided a recess 45 within which is positioned the condenser 46. Arranged in engagement with the boss 26, formed in the end plate 20, is an annular housing member 47 provided with an end cover plate 48. The interrupter contacts are mounted on the housing 47, and as the housing 47 is merely frictionally mounted on the boss 26, it may be adjusted about the boss in a rotary direction in order to determine the time of operation of the interrupter. The housing 47 is provided at one side with a projecting lug or arm 49 to facilitate the rotary adjustment of the housing.

10 20 Insulatably mounted on the inner surface of the housing 47, in any desired manner, is the fixed interrupter contact 50. Pivotally supported at 51 is the movable interrupter arm 52 provided at one end thereof with the 15 contact 53 and intermediate its ends with an insulating block 54 adapted to be engaged by the oppositely disposed cam element 55 carried by the cam collar 56, which is non-rotatably secured to the free end of 30 the pintle 28 by means of the nut 57.

Extending through the cover plate 48 is a binding post 58 which is insulated from the plate 48 by means of the insulating collar 59. A spring finger 60 is electrically 35 connected to the stationary contact 50 of the interrupter and bears adjacent its free end on the inner end of the binding post 58. The conductor 61, one end of which is secured to the binding post by means of 40 the nut 62, has its other end joined to the non-grounded end of the primary coil 36. The conductor 63 has one end connected to the non-grounded end of the secondary coil 37, and the other end extends to a spark 45 plug or the usual flyer of a distributor.

Extending outwardly from the end plate 20 is a post 64, to the outer end of which is secured a spring finger 65 arranged to engage the housing cover plate 48 and thus 50 maintain the interrupter housing in position.

The operation of the device is as follows: It will be noted that when the laminations of the inductor 31 extend substantially horizontally, one end of the inductor will be adjacent to a pole piece of the magnets 10 and 11, while the other end of the inductor will be adjacent to the opposite pole piece of the magnets 13 and 14. Thus flux will 55 flow through the inductor element 31 about which is positioned the generator coil 42. As the inductor is rotated the magnetic lines will be cut, thus inducing current in the coil 42. In parallel with the path 60 through the central portion of the inductor

element 31 is another path from the same pole piece, which will extend from the pole piece through the adjacent end section of the inductor to the collar 40 or 41 on the extensions for the core 35, thence through the core 35 to the other collar 40 or 41 and to the opposed pole piece at the opposite corner of the magneto. Thus, as the inductor is rotated, the change in the flux flowing through the core 35 will tend to set up currents in the primary coil 36, and likewise in the secondary coil 37 of the transformer. The generator and primary coils are so wound, however, that these currents set up in the primary coil 36 and the generator coil 42 will not interfere with each other, but will find a common return path to the grounded sides thereof through the interrupter contacts 50 and 53 which are now closed. At approximately the instant that the inductor ends leave the pole pieces with which they have been in engagement, the interrupter contacts will be opened. Now the current flowing through the coils 42 and 36 can no longer find a common return path through the interrupter contacts 50 and 53 and the current induced in one of these coils will, therefore, oppose that induced in the other. The surge of current existing in the coil 42 will operate to reverse the current flowing through the coil 36, thus setting up a high potential impulse in the secondary coil. This effect will also be augmented by the discharge from the condenser 46 which follows the opening of the interrupter contacts.

While in the drawings and above description a single set of details have been set forth, it is to be understood that certain modifications are contemplated by applicant and the invention, therefore, is to be limited only by the scope of the appended claims.

Having now described my invention, what I consider as new and desire to secure by Letters Patent of the United States is:

1. In a magneto, a permanent magnet having two pairs of separated pole pieces, there being one of each polarity in each pair, a rotor positioned between said pairs of pole pieces, a unitary inductor extending longitudinally of said rotor having its opposite ends offset, one of said offset ends being arranged to pass in proximity to two of said pole pieces of opposite polarity, and the other offset end being arranged to pass in proximity to the other two pole pieces, a primary and a secondary coil, a core for said coils having end projections adjacent said pole pieces and the path of said inductor, and a generator coil about said inductor element, said generator coil being connected in parallel with said primary coil.
2. In a magneto, a permanent magnet having two pairs of separated pole pieces,

there being one of each polarity in each pair, a rotor positioned between said pairs of pole pieces, a unitary inductor extending longitudinally of said rotor having its opposite ends offset and arranged to complete paths from a pole piece of one pair to a pole piece of the other pair twice during each revolution of said rotor, a generator coil about said inductor element, a second coil, a core for 5 said second coil, extensions for said core adjacent to the path of said inductor element, said offset ends of said inductor element being arranged to complete paths from said pole pieces to said extensions, a circuit extending in parallel to the non-grounded terminals of said coils, and an interrupter 10 in said circuit.

3. In a magneto, a permanent magnet having two pairs of separated pole pieces, there 15 being one pair of each polarity, a rotor positioned between said pairs of pole pieces,

a unitary inductor extending longitudinally of said rotors and having its opposite ends offset, one of said offset ends being arranged to pass in proximity to two of said pole pieces of opposite polarity and the other offset end being arranged to pass in proximity to the other two pole pieces, a generator coil about said inductor element, a second coil, a core for 25 said second coil, extensions for said core adjacent to the paths of said offset ends and magnetically insulated from said pole pieces, said offset ends being arranged to complete magnetic paths from said pole pieces to said core extensions, a 30 circuit extending in parallel to the non-grounded terminals of said coils, and an interrupter in said circuit.

In witness whereof, I hereunto subscribe my name this 14th day of March, 1922.

WILLIAM W. HAWKINS.
